DOOR FASTENER

Syver O. Tveden, Chicago, Ill.

Application March 2, 1936, Serial No. 66,680

1 Claim. (Cl. 292—67)

This invention relates to door fasteners, particularly designed for use in cases where an outer steel door supplements an inner door and is latched from the inside. Such combination of doors is in common use at the rear or alley entrance to stores and in places where it is desirable to have the fastener inaccessible from the outside and of such construction that the ordinary tools which might be used for ripping a hasp loose from the outside would not be serviceable for disengaging the improved fastener.

The objects of the invention are to provide a door fastener which is strong, durable, has free and simple elements and is operable from the inside by some such simple means as a socket wrench.

The improved construction is illustrated in the accompanying drawing wherein:—

Figure 1 shows in plan the improved door fastener with associate doors and door frame shown in section.

Fig. 2 is an enlarged view of the fastener showing it in plan and partly in horizontal section and in place in a door jamb which is also shown in section.

Fig. 3 is a face view of the fastener as indicated by the arrows 3—3 of Fig. 2.

The essential elements of the improved door fastener are a bolt which is slidable in a transverse aperture in a door jamb with the head of the bolt at the inside of the jamb and a cooperating latch element which depends from a bar on an outer door and is slidable on said bar, so that a lug carried on the depending element may be moved into a recess in the door jamb in position for receiving the threaded end of the bolt, the lug having a threaded aperture for this purpose.

By means of a fastener so constructed, it is possible to provide a door-securing means which is inaccessible from the outside, even though the outer door which it secures is an open grill.

The lug-carrying element referred to is indicated in the drawing by the numeral 1 and carries, integral or welded, lug 2 which lug is provided with a threaded aperture 3. The lug-carrying element 1 is supported on a horizontal guide or bar 4 which is welded or riveted to an outer steel door 5.

The latch element 1 may be slid along the bar 4 to cause the lug 2 to enter a recess 6 in the door jamb or frame member 7.

The locking bolt 8 is supported in a transverse aperture 9 in the door jamb, has a head 10 for receiving a socket wrench, and is threaded at its opposite end 11 to fit the threaded aperture 3 in lug 2. The door jamb adjacent the fastener is faced with a steel plate 12 secured to the door jamb by screws 13 and carrying welded thereto a metal facing 14 for the recess 6.

The door 5 may be solid or of open construction but the head of the latching bar faces inwardly and is inaccessible from the outside, particularly when the inner door 17 is closed. The doors 5 and 17 swing on the hinges 15 and 16 and when the door 5 is open the latching element 1 depends from the bar 4.

When it is desired to fasten the outer door 5 in closed position, the element 1 is swung upwardly on its support 4 and then slid along the support to cause the lug 2 to enter recess 6, and thus the threaded aperture in the lug comes into alignment with the bolt. By screwing the bolt into the lug, the latching element 1 is retained against movement along the bar 4 and thus the outer door cannot be swung outwardly on its hinges 15 without unscrewing the bolt 10. To open the outer door, the bolt must be unscrewed and the latching element 1 slid by hand along the bar 4 to its inoperative position, as indicated by dotted lines in Fig. 1.

I claim:

In a lock construction for use in connection with inner and outer doors for locking the outer door from the inner side of the inner door, comprising a bar secured to and parallel with the outer door, a latch element slidable on the bar and rotatable thereon in different planes at right angles to the door, a lug carried by said latch element and extending therefrom in a plane parallel to the door, said lug being apertured for reception of a screw, a keeper plate mounted on the door jamb and having a recess for receiving the lug of said latch element, and a locking screw adjustably mounted in said keeper plate to move transversely to the sliding movement of the latching element and to engage the lug at the aperture therein.
